UNITED STATES PATENT OFFICE.

PETER W. TRIMBORN AND CARL BARKHAUSEN, OF MILWAUKEE, WISCONSIN.

GARBAGE AND REFUSE INCINERATOR.

Application filed January 8, 1923. Serial No. 611,364.

To all whom it may concern:

Be it known that PETER W. TRIMBORN and CARL BARKHAUSEN, citizens of the United States, residing at Milwaukee, county of Milwaukee, and State of Wisconsin, have invented new and useful Improvements in Garbage and Refuse Incinerators, of which the following is a specification.

Our invention relates to improvements in 10 garbage and refuse incinerators.

The object of our invention is to provide an improved incinerator which will be odorless and which is capable of utilizing as fuel, oil, coal dust or wood; also to provide an 15 automatic system for pre-heating the garbage or other refuse, feeding it into the combustion chamber, withdrawing unburned gases from above the material and feeding such gases through the fire, whereby the obnoxious 20 gases may be wholly consumed and the products of combustion finally delivered through the stack in a substantially odorless condition.

In the drawings:-

25 Figure 1 is a vertical sectional view of an improved incinerator embodying the invention, the section being drawn to a plane which includes the axes of the return flues for burning the gases.

30 Figure 2 is a sectional view at right angles to Fig. 1 drawn on line 2—2 of Fig. 1.

Figure 3 is a sectional view drawn on line 3—3 of Fig. 2.

35 Figure 4 is a sectional view drawn on line 4—4 of Fig. 2.

Like parts are identified by the same reference characters throughout the several views.

40 In the drawings, A indicates sliding doors through which the material is delivered to the incinerator into hoppers B.

45 C are ducts for the return of gases to the fire, D are grates disposed between the upper and lower margins of the hopper and inclined downwardly toward the walls B' to form upper and lower portions of the hopper, E are inclined grates and F are dumping grates. G is a conveyor for the ashes and incombustible material dropping from the combustion chamber H. I is the

chimney to which communication is had through the openings I' and I''.

The walls B' of the hoppers B subdivide the hopper space into two sections. The material, as it dries and bakes in the hopper 55 sections, slides down along the walls B' until it passes the grates D, whereupon it drops upon the auxiliary grates D' which are adapted to tilt and deliver the material into the fire-pot and indirectly the grates D' 60 assist in such regulation by directing the materials toward the inclined walls B'.

The ducts C are equipped with suction fans for positively withdrawing the gases from the upper portion of the hopper chamber and delivering them into the ash-pit underneath the fire-pot, i. e., underneath the grates E. Such fans are indicated at K.

The blast of air and gas delivered by the fans through the horizontal runs C' of the 70 ducts C produces an aspirating effect in the auxiliary ducts C'' which take the gases from beneath the inclined grates D. This aspirating effect is increased by baffles L which extend obliquely from one side partially across the lower end of each of the ducts C''.

The heat of the fire in the combustion chamber H is relied upon to dry out the material in the hoppers B. The material in 75 the lower portion of the hoppers between the inclined grates D and the tilting grates D' becomes very thoroughly dried. The walls B' define a closed hot chamber above the arch b, this chamber having no inlet and

the chimney outlet I'' being intended merely to relieve the chamber from internal pressure due to heat. Therefore, the walls B' may be raised to such a temperature that material falling thereon is very rapidly 80 dried and brought into condition for burning and as this material passes most readily downwardly to the portion of the hopper below the grates D, the other materials are directed by said inclined grates D toward 85 these hot walls B' so that substantially all material is brought into contact with or close proximity to said walls before reaching the fire-pot.

To support combustion in the fire-pot the 100

fuel is delivered thereto under air pressure. It is, therefore, possible to use oil, or other liquid fuel, or to use solid fuel which, if desired, may be in finely subdivided form.

5 We claim:

1. In a garbage incinerator, the combination with a fire-pot, of a superposed receiving hopper having an inclined wall and a co-operating wall, said inclined wall being 10 inclined downwardly toward said co-operating wall, and a grate downwardly and inwardly inclined from the co-operating wall toward the inclined wall intermediate the upper and lower margins of said hopper, thereby to subdivide said hopper into upper 15 and lower portions.

2. In a garbage incinerator the combination with a fire-pot, of a superposed receiving hopper having inner walls downwardly 20 and outwardly inclined and outer walls, and grates downwardly and inwardly inclined from the outer walls of the hopper toward said inner walls at points between their upper and lower margins, said grates 25 partially subdividing the hopper into upper and lower portions.

3. In a garbage incinerator, the combination with a fire-pot, of a superposed receiving hopper having inner walls downwardly and outwardly inclined and outer walls, and grates downwardly and inwardly inclined from the outer walls of the hopper toward intermediate portions of the inner walls, said grates partially subdividing the 30 hopper into upper and lower portions, and tilting grates at the bottom of the hopper adapted to deliver material therefrom into the fire-pot.

4. In an incinerator, the combination of 40 a fire-pot provided with a superposed arch, inclined hot plates extending upwardly from the margins of the arch and convergingly to form an apex, co-operating inclosing walls forming with said hot plates, 45 a hopper having an opening at its top through which material may be delivered into the hopper, tilting grates disposed between the margins of said arch and said inclosing walls, said grates being adapted 50 in one position to support material in the path of the flame and gases of combustion coming from the fire-pot and adapted in another position to permit such material 55 to pass from the hopper into the fire-pot, and co-operating grates partially subdividing the hopper into upper and lower sections, and inclined inwardly from the inclosing walls to thereby direct material from the upper section to the lower section 60 along the surfaces of said inclined hot plates and away from said inclosing walls.

5. In a garbage incinerator the combination of an enclosing chamber provided with a grated fire-pot in its lower portion, a 65 superposed arch spaced from walls of the

enclosing chamber at the respective sides of the arch, tilting grates in said spaces adapted to regulate delivery of material to the fire-pot from the space above the grates, upwardly converging hot plates 70 above the arch, and means for delivering material from the upper portion of the chamber inwardly and downwardly toward said hot plates, whereby such material is caused to slide downwardly along the hot 75 plates to said grates.

6. In a garbage incinerator the combination of an enclosing chamber provided with a grated fire-pot in its lower portion, a superposed arch spaced from walls of the 80 enclosing chamber at the respective sides of the arch, tilting grates in said spaces adapted to regulate delivery of material to the fire-pot from the space above the grates, upwardly converging hot plates above the 85 arch, means for delivering material into the upper portion of the chamber downwardly upon and along said hot plates to said grates, and a set of feed regulating grates controlling the downward movement of material along said hot plates.

7. In a garbage incinerator the combination of an enclosing chamber provided with a grated fire-pot in its lower portion, a superposed arch spaced from walls of the 95 enclosing chamber at the respective sides of the arch, tilting grates in said spaces adapted to regulate delivery of material to the fire-pot from the space above the grates, upwardly converging hot plates above the 100 arch, and means for delivering material into the upper portion of the chamber downwardly upon and along said hot plates to said grates, and a set of feed regulating grates controlling the downward movement 105 of material along said hot plates, said enclosing chamber walls being provided with ducts leading from the upper portions of the chamber downwardly to points beneath the fire-pot, whereby gases of combustion 110 may pass through the material above the tilting grates and then downwardly with vapors from such material to be delivered through the fire from below.

8. In a garbage incinerator a chamber 115 subdivided by partition walls and gratings into an upper material receiving hopper section, a lower material supporting hopper section, a fire-pot, and an ash-pit having ducts leading, respectively, from both hopper sections to the ash-pit, and power driven means for maintaining a forced circulation upwardly from the fire pot through the material in the hopper sections and downwardly in said ducts.

9. In a garbage incinerator a chamber subdivided by partition walls and gratings into an upper hopper section, a lower hopper section, a fire-pot, and an ash-pit having 120 ducts leading, respectively, from both 125

hopper sections to the ash-pit, and power driven means for maintaining a forced circulation downwardly in said ducts, one of said ducts being provided with a power driven impeller, and another of said ducts being arranged with its lower end connected to the outlet portion of the first mentioned ducts and provided with a baffle adapted to utilize the aspirating effect developed by the impeller to cause a downward circulation in the cooperating duct. 10
